UNITED STATES PATENT OFFICE.

SAMUEL H. LYON AND WM. E. DOUBLEDAY, OF BROOKLYN, NEW YORK.

BONNET.

Specification of Letters Patent No. 31,724, dated March 19, 1861.

To all whom it may concern:

Be it known that we, SAMUEL H. LYON and WILLIAM E. DOUBLEDAY, of Brooklyn, in the county of Kings and State of New 5 York, have invented, made, and applied to use a certain new and useful Improvement in Bonnets or Hats; and we do hereby declare that the following is a full and exact description of our said invention.

10 Frames of buckram, bonnets of straw and willow have been pressed out of one piece of material between dies, and woolen cloth has been pressed up into the form of a hat, but a want has been experienced by the 15 community of a light cheap durable and handsome bonnet bloomer or hat adapted to ladies' use especially in summer when woolen, straw willow, or similar bonnets are too heavy and warm.

20 To meet this demand we have devised the present invention.

We have discovered that the article known 25 as pique or marseilles, that is formed of cotton, woven into various figures, when laid upon buckram, and the two caused to adhere by paste or by the sizing of the buckram and pressed into shape, out of one piece between dies, will form a neat light, handsome durable and cheap bonnet or hat 30 adapted to ladies' wear; to produce the said bonnet bloomer or hat, we pursue the proc-

ess before indicated; we cause the flat sheets of pique and buckram or similar stiffening to adhere to each other and we prefer that they be dried, and afterward sufficiently 35 dampened for pressing into form between heated dies of the desired shape, or the flat sheets may be pressed into shape before they become quite dry. We thus produce a new and useful article of manufacture

40 In the accompanying drawings we have represented a bonnet (Figure 1) and a bloomer (Fig. 2). In these the interior *a*, is the aforesaid stiffening, and *b*, is the pique or marseilles exterior, the two adhering as 45 before set forth.

What we claim and desire to secure by Letters Patent as a new article of manufacture is—

The bonnet or hat formed of cotton cloth 50 known as pique or marseilles upon buckram or stiffening material and pressed into form between heated dies as set forth.

In witness whereof we have hereunto set our signatures this third day of October 55 1860.

S. H. LYON.
WM. E. DOUBLEDAY.
